United States Patent Office

Des. 225,512
Patented Dec. 19, 1972

225,512

COVERED HOT FOOD TRAY

Steven J. Cyr and Mark W. Whelan, Chippewa Falls,
Wis., and John A. Krause, Tucker, Ga., assignors to
Standard Oil Company, Chicago, Ill.

Filed Dec. 16, 1970, Ser. No. 26,537

Term of patent 14 years

Int. Cl. D9—03

U.S. Cl. D9—185

Fig. 1

Fig. 2

FIG. 1 is a top plan view of a covered hot food tray showing our new design.

FIG. 2 is a rear elevation thereof.

FIG. 3 is a front elevation thereof.

FIG. 4 is a side elevation thereof, the side opposite being a mirror image thereof.

FIG. 5 is a plan view thereof in fully open position showing the interior surfaces.

FIG. 6 is a plan view thereof in fully open position showing the exterior surfaces.

We claim:

The ornamental design for a covered hot food tray, as shown and described.
